UNITED STATES PATENT OFFICE.

ALFRED ADAMSON, OF LYNN, MASSACHUSETTS.

FRICTIONAL REVERSING-GEAR.

SPECIFICATION forming part of Letters Patent No. 758,494, dated April 26, 1904.

Application filed May 19, 1903. Serial No. 167,845. (No model.)

To all whom it may concern:

Be it known that I, ALFRED ADAMSON, a citizen of the United States, residing at Lynn, in the county of Essex and State of Massachusetts, have invented certain new and useful Improvements in Frictional Reversing-Gears; and I do hereby declare the following to be a full, clear, and exact description of the invention, such as will enable others skilled in the art to which it appertains to make and use the same.

My invention relates to improvements in frictional reversing-gearing, and is especially applicable for use with motor-vehicles or the like, although it is obvious that it may be used in various other connections.

Briefly stated, my invention comprises a pair of gear-wheels so coöperating between the driving mechanism of the motor and the driven shaft of the motor-vehicle or the like as to reverse the direction of rotation of said driven shaft as may be desired.

The present invention is particularly designed as an improvement on my United States Letters Patent No. 673,071, granted April 30, 1901. In that patent the intermediate gear-wheels are mounted on an arm or yoke pivotally supported on a longitudinal axis so that when thrown in mesh with the driving and driven wheels they assume a plane angular to the driving and driven wheels; but in the present instance the gear-wheels are rotatably shifted in a strictly vertical plane, and hence engage the driving-wheels in the same plane of rotation—a manifest advantage.

Other objects and advantages will appear in the following specification, and to more fully describe my invention reference is had to the accompanying drawings, in which like letters designate corresponding parts, and in which—

Figure 1 is a side elevation of my improved reversing-gearing, the driving-wheel A being omitted; and Fig. 2 is a plan of same, both driving-wheels being shown.

A A' designate a pair of driving-wheels rigidly mounted on the power-shaft *a* of the motor or engine; B and C, the gear-wheels mounted on the shafts *b* and *c*, respectively, and D a gear-wheel mounted on the shaft *b*

alongside the wheel B and adapted to mesh with the gear-wheel C. These wheels, as clearly shown in Fig. 2, are circumferentially grooved, so as to form beveled ribs alternating with V-shaped grooves, the beveled ribs of one wheel entering the V-shaped grooves of its adjacent wheel when in engagement, thereby obtaining greatest possible surface contact between the wheels in a vertical plane.

Pivots supported centrally on the pivot-rod E, on each side of the gear-wheels, are the upright arms F, provided at their upper ends with the rectangular slotted heads G G' and at their lower ends with the journal-bearings H.

The pivot-rod E, as clearly shown, is supported in a suitable bearing or frame I, which in turn is adapted to rest on the angle-irons supporting the engine or motor or otherwise, as may be desired.

In the journal-bearings H, at the lower ends of the arms F, is suspended the shaft *c* of the large gear-wheel C, and mounted in the slotted heads G and G', at the upper ends of the arms F, are located the journal guide-blocks *b'*, adjustable longitudinally therein by the set-screws *g* *g'* and the nuts *f* *f'*. In these journal guide-blocks is mounted the shaft *b*, carrying the gear-wheels B and D.

Suitably mounted on the lower shaft *c* is a sprocket-wheel J, and in actual operation this sprocket-wheel is geared by a sprocket-chain 80 with a similar sprocket-wheel on the driven axle of the motor-vehicle or the like, or any other equivalent connection between the shaft *c* and the driven shaft may be used, if desired.

The arrangement of the various wheels is such relatively to each other, as clearly shown in Fig. 2, that the gear-wheels B and C may alternately be thrown in and out of engagement with their respective driving-wheels A' and A. The small gear-wheel D, being disposed alongside the large gear-wheel B, rests on the gear-wheel C and is held in adjustable engagement therewith by the arms F and the adjusting means above referred to.

K is a substantially U-shaped yoke or member secured in any suitable manner to the arms F. In the drawings I have illustrated this yoke member as being secured at its free

ends, as by the bolts *k*, to the slotted heads *G G'* of the arms *F*. Connected to said yoke at its upper end is a rod *L* or other suitable connection for operating the gear-wheels on their common pivotal axis *E* into and out of engagement with the driving-wheels in a longitudinal vertical plane. This rod or connection at its free end may be pivotally connected to a handle (not shown) in easy reach of the operator.

Assuming the parts to be in the position shown in Fig. 1, the driving-wheels *A A'* rotating to the right, as indicated by the arrow, the upper gear-wheel *B* being in mesh and the lower gear-wheel *C* out of mesh with their respective driving-wheels, then the driving-wheel *A'* rotates the gear-wheel *B*, together with the gear-wheel *D*, to the left, the latter meshing with the gear-wheel *C*, rotating it to the right or in the same direction as the driving-wheel. Upon a backward pull on the rod *L* the upper gear-wheel *B* is thrown out of mesh with its driving-wheel *A'* and the lower gear-wheel *C* is thrown in mesh with its driving-wheel *A*. The gear-wheel *C* being then directly geared to its driving-wheel is rotated in an opposite direction to the direction of rotation when operated through the intermediate gears *B* and *D*, and hence the direction of rotation of the sprocket-wheel *J* is reversed, and correspondingly the driven shaft or axle of the vehicle.

It is obvious that if it is desired to throw and hold both of the reversing gear-wheels out of engagement with the driving-wheel, so that the engine or motor may be allowed to run without operating the other mechanism, it is only necessary that the arms *F* be rotated on their axis a limited distance—that is to say, sufficiently so to throw one reversing-gear just out and the other one not quite into engagement with the driving-wheel.

I do not wish to limit myself to the exact details of construction as herein described, as it is obvious that many modifications might be made without departing from the spirit of my invention; but

What I claim, and desire to secure by Letters Patent of the United States, is—

1. In reversing-gearing, the combination with driving means, of a pair of reversing gear-wheels and means so connecting same as to rotate one of said wheels by, and in the opposite direction to the direction of rotation of, said other wheel, and means for simultaneously throwing one of said gear-wheels into and the other out of engagement with the driving means.

2. In reversing-gearing, the combination with driving means, of a pair of reversing gear-wheels, conjointly movable in parallel planes, means so connecting said gear-wheels as to rotate one of said wheels by, and in the opposite direction to the direction of rotation of, said other wheel, and means for simulta-

neously throwing one of said wheels into and the other out of engagement with the driving means.

3. In reversing-gearing, the combination with a pair of driving-wheels, of a pair of reversing gear-wheels, a pinion carried by one of said reversing-gears and meshing with the other for rotating said geared wheels in opposite directions, and means for simultaneously throwing one of said geared wheels into and the other out of engagement with their respective driving-wheels.

4. In reversing-gearing, the combination with driving means, of a pair of reversing gear-wheels, conjointly movable in parallel planes adjacent said driving means, a pinion carried by one of said reversing-gears and meshing with the other for rotating said geared wheels in opposite directions, and means for throwing one of said geared wheels into and the other out of engagement with the driving means.

5. In reversing-gearing, the combination with the pair of driving-wheels, of a pair of reversing gear-wheels, conjointly movable in parallel planes, a pinion carried by one of said reversing-gears and meshing with the other for rotating said geared wheels in opposite directions, and means for simultaneously throwing one of said geared wheels into and the other out of engagement with their respective driving-wheels.

6. In reversing-gearing, the combination with the driving means, of a pair of reversing gear-wheels, a pinion carried by one of said reversing-gears and meshing with the other for rotating said geared wheels in opposite directions, and means for simultaneously throwing one of said wheels into and the other out of engagement with the driving means, comprising an arm connecting the respective shafts of said wheels, for holding said wheels always in gear, and means for operating said arm.

7. In reversing-gearing, the combination with the driving means, of a pair of reversing gear-wheels, conjointly movable in parallel planes, a pinion carried by one of said reversing-gears and meshing with the other for rotating said geared wheels in opposite directions, and means for simultaneously throwing one of said wheels into and the other out of engagement with the driving means, comprising an arm connecting the respective shafts of said wheels, for holding said wheels always in gear, and means for operating said arm.

8. In reversing-gearing, the combination with the driving means, of a pair of geared wheels conjointly movable in parallel planes, and means for simultaneously throwing one of said wheels into and the other out of engagement with said driving means, comprising an arm and co-operating means adjustably connecting the respective shafts of said wheels, for holding said wheels always in gear, and means for operating said arm.

9. In reversing-gearing, the combination with driving means, of a pair of gear-wheels and gearing therebetween adapted to rotate said gear-wheels in opposite directions, and means for simultaneously throwing one of said gear-wheels into and the other out of engagement with the driving means, comprising an arm connecting the respective shafts of said gear-wheels, for holding said wheels always in gear and conjointly movable in parallel planes, and means for operating said arm.

10. In reversing-gearing, the combination with the driving means, of a pair of reversing gear-wheels, a pinion carried by one of said reversing-gears and meshing with the other for rotating said geared wheels in opposite directions, a pair of pivoted arms connecting the respective shafts of said wheels for supporting and holding said wheels geared, and means for rotating said pair of arms on their axis for simultaneously throwing one of said wheels into and the other out of engagement with the driving means.

11. In reversing-gearing, the combination with a pair of driving-wheels, of a pair of gear-wheels and gearing therebetween adapted to rotate said gear-wheels in opposite directions, a pair of pivoted arms connecting the respective shafts of said gear-wheels for supporting and holding said wheels geared, and means for rotating said pair of arms on their axis for simultaneously throwing one of said gear-wheels into and the other out of engagement with their respective driving-wheels.

12. In reversing-gearing, the combination with the driving means, of a pair of reversing gear-wheels, a pinion carried by one of said reversing-wheels and meshing with the

other for rotating said geared wheels in opposite directions, and means for simultaneously throwing one of said geared wheels toward and the other away from the driving means a limited distance for holding both of said geared reversing-wheels out of engagement with the driving means.

13. In reversing-gearing, the combination with the driving means, of a pair of reversing gear-wheels conjointly movable in parallel planes, a pinion carried by one of said reversing-gears and meshing with the other for rotating said geared wheels in opposite directions, and means for simultaneously throwing one of said geared wheels toward and the other away from the driving means a limited distance, for holding both of said reversing-wheels out of engagement with the driving means.

14. In reversing-gearing, the combination with the driving means, of a centrally-pivoted arm adjacent thereto, a pair of reversing gear-wheels mounted in the respective ends of said arm, gearing directly connecting, said reversing gear-wheels adapted to rotate said gear-wheels in opposite directions, and means for operating said arm a limited distance on its pivotal axis for throwing one of said reversing-wheels toward and the other away from the driving means and holding both of said reversing gear-wheels out of engagement with said driving means.

In testimony whereof I affix my signature in presence of two witnesses.

ALFRED ADAMSON.
